UNITED STATES PATENT OFFICE.

WILLIAM S. PIERCE, OF FRANKLIN, PENNSYLVANIA.

SWAGE FOR USE IN OIL-WELLS.

1,327,491.

Specification of Letters Patent.

Patented Jan. 6, 1920.

Application filed July 31, 1917, Serial No. 183,719. Renewed June 21, 1919. Serial No. 305,872.

To all whom it may concern:

Be it known that I, WILLIAM S. PIERCE, a citizen of the United States, residing at Franklin, in the county of Venango and

5 State of Pennsylvania, have invented certain new and useful Improvements in Swages for Use in Oil-Wells; and I do hereby declare the following to be a full, clear, and exact description of the invention, such as will enable others skilled in the art to which it appertains to make and use the same.

10 My present invention relates to improvements in swages for use in oil wells or the like. In these wells the casing is apt to become weak through rust and corrosion, and since this casing must bear its own weight as well as that of the pumping apparatus, and more or less pressure from the outside, 15 also, when it becomes weakened to a certain point it collapses and crumbles.

20 At the point where the collapsing takes place the casing is often very much mutilated and slivered, the points of metal projecting inwardly in various shapes.

25 These collapsed portions form obstructions in the well, and it is desirable to open up these obstructions in order to provide a passage for a packer, a casing cutter, or 30 other device to be used at a point under that at which such collapsing has occurred.

35 My present invention consists in the construction of such a device as will open up a collapsed casing, and the invention will be more fully understood by reference to the accompanying drawing, in which:

40 Figure 1 shows a section through the well casing, the inner tube being shown in elevation and the swage block being shown partly in section and partly in elevation;

45 Fig. 2 shows a section along the line 2—2 of Fig. 1, and looking down; and

50 Fig. 3 shows a section through the axis of the swage block.

55 A represents the well casing which is shown as crumbled in at a. B represents the inner tube made up of sections in the usual way, which sections are connected together by the coupling rings C.

60 When the parts are assembled, these rings form, in effect, set collars spaced at equal distances on the inner tube B.

65 Mounted on one of the sections of this inner tube B, between a pair of these coupling

70 rings C, is the swage block D, which is preferably in the form of two truncated cones

joined at their bases, these two cones being provided with wedging surfaces d, d' and with striking ends d², which are adapted to engage the coupling rings C.

60

These swage blocks are bored so as to slide freely on any one of the sections of the inner tube, between adjacent coupling rings.

The operation of the device is as follows:

65 The collapsed portion a of the well casing being located, the inner tube is pulled up a sufficient distance, the swage block is put on, and the inner tube is lowered down again with the swage block mounted thereon. When the swage block meets the obstruction a it will be raised, and the entire weight of the inner tube, with the parts carried thereby, will strike a blow like a great hammer on the upper end of the swage block, and will wedge it down through the 70 crumbled portion of the casing. The blow may be repeated as often as desired, by raising the inner tube and letting it fall again.

75 By having the swage block tapered in both directions, as shown at d, d', it may be 80 wedged upward through the crumbled portion of the well casing by hoisting up on the inner tube.

85 While the inner tube forms a convenient mounting for the swage block, it will be obvious that similar results, as herein described, may be accomplished by using, instead of the inner tube, any rigid member which can be lowered into the well, and is provided with set collars between which the 90 swage block is slidably mounted.

95 In either case there will be a downward jar or hammer blow by letting the inner member fall, causing the upper collar to strike the swage block, while the upward jar may be produced by hoisting the inner member upward, causing the lower collar to strike the lower edge of the swage block.

100 While I have shown the angle of the two cones constituting the swage block as the same, one of the cones, for instance the lower one, might be of a sharper angle than the other, thus securing greater wedging effect.

105 Having thus described my invention, what I claim and desire to secure by Letters Patent of the United States is:

110 In a device for use in wells of the character described, the combination with a tube composed of a series of sections connected together by coupling rings projecting beyond the outer surface of the tube and forming set collars thereon, of a swage block slid-

ably mounted on said tube between a pair of adjacent collars, the said swage block being substantially in the form of two truncated cones with their bases joined, the maximum transverse diameter of the swage block being slightly less than the inner diameter of the well casing to be expanded, the said swage block having an axial bore

slightly larger than the periphery of the member whereon said swage block slides, 10 the ends of said swage block being adapted to be struck by one or the other of said collars as said tube is raised or lowered, substantially as described.

In testimony whereof, I affix my signature. 15
WILLIAM S. PIERCE.
